(57) CLAIM

The ornamental design for a lamp for nails, as shown and described.

DESCRIPTION

FIG. 1 is a top plan view of a lamp for nails showing my new design;

FIG. 2 is a front elevational view thereof;

FIG. 3 is a bottom plan view thereof;

FIG. 4 is a rear elevation thereof;

FIG. 5 is a left side elevation of the lamp for nails, the right side elevation is the same;

FIG. 6 is a left side elevation of the lamp for nails shown without the left cover for the purpose of showing a portion of the interior;

FIG. 7 is a front isometric view of my design; and,

FIG. 8 is a rear isometric view of the lamp for nails showing my design.
